UNITED STATES PATENT OFFICE.

PURCHES MILES, OF BROOKLYN, NEW YORK.

WIRE HOOK.

SPECIFICATION forming part of Letters Patent No. 392,624, dated November 13, 1888.

Application filed April 3, 1888. Serial No. 269,461. (No model.)

To all whom it may concern:

Be it known that I, PURCHES MILES, of Brooklyn, in the county of Kings and State of New York, have invented certain new and useful Improvements in Wire Hooks for Coats, Hats, &c.; and I do hereby declare that the following specification, taken in connection with the drawings furnished and forming a part of the same, is a clear, true, and complete 10 description of my invention.

My said improvements relate to what may be termed "double hooks," composed of a single length of wire so bent as to afford a main hook and another underlying hook, and have 15 a screw-threaded shank. Hooks have heretofore been so constructed that each of said separate hooks is composed of two portions of the wire, and one terminal of the wire extends from said lower hook upward to and around 20 the shank of the upper hook, and that portion of the wire extending from the front of the upper hook downward and rearward to the lower hook serves as a brace for said upper or main hook, because the rear of the lower hook when 25 in service abuts against the surface on which the hook is mounted, all as disclosed in my Letters Patent No. 280,062, dated June 26, 1883. In mounting these prior double hooks there is a liability of a defacing contact of the 30 rear of the lower hook with the surface on which it is to be mounted during the final rotative movements of the hook while driving the screw-shank into wood far enough to provide for a firm abutting contact of said lower hook with the surface of the wood, thus involving a liability of objectionable abrasion 35 of said surface in circular or semicircular lines.

The objects of my present improvements are to not only obviate this liability of defacement, but to also provide, in a cheap grade of goods, a strong reliable lower hook with a minimum of wire and without the aid of such complex mechanism as is necessary for forming double hooks which have a lower hook-shank suspended by means of an eye thereon from the screw-threaded shank. All of said ends are attained by me, because my novel hook is composed of a single length of wire, has a straight shank which is screw-threaded 45 at its tip, is bent to form a hook at the outer end of the shank, is extended downward and

rearward therefrom, and developed into an underlying hook composed of a single line of wire, and with this I combine a strap or loop which couples the straight shank with the 55 lower hook, and is adjustable longitudinally on said shank. In mounting a hook thus constructed, the screw-shank is turned into the wood nearly to the extent desired, and then, the link having been first moved forward out 60 of its normal position, the lower hook is or can be sprung out of its normal position, so that the final turning of the shank can be effected without contact of the hook with the surface of the wood, and then the lower hook 65 is pressed into close contact with said surface and the link moved into its proper position, thus providing for the proper bracing effect between the back of the lower hook and the upper hook. If, however, my novel hooks 70 are desired without reference to said non-abrasive capacity, said links may be permanently fixed in position, such a hook being simpler, lighter, and less expensive than my prior double hooks.

To more particularly describe my invention, I will refer to the drawings, in which—
Figure 1 illustrates in side view one of my hooks as when applied for service. Fig. 2 illustrates the same as when in position just 80 prior to the final turning of the screw-shank. Fig. 3 in side view illustrates a detached coupling-link in a desirable form composed of wire. Fig. 4 in several views illustrates a detached sheet-metal link, and also the same as when 85 crimped into form when in its proper and effective place on the hook.

The hook is composed of a length of wire, and it has the straight shank *a*, having a screw-threaded tip, and at its opposite end the main 90 hook *b* is formed by bending the wire upward, forward, and downward, thence rearward under the shank, where the other terminal of the wire is developed into a second or lower hook, *c*, underlying said shank, and having a sur- 95 face, *c'*, at its rear for abutting against the surface on which the hook may be mounted, and affording a bracing effect for the upper hook. The coupling-link *d*, in a desirable form, is composed of wire and is S-shaped, so 100 as to embrace the wire of the shank and the underlying brace portion, and to confine them

in fixed positions with reference to each other. In its best arrangement said link can be moved longitudinally on the hook, so that when moved toward the hook *b*, as indicated in Fig. 2, the hook *c* can be readily deflected and enable its abutting surface at *c'* to be kept from contact with the surface on which it is to be mounted during the final turning of the screw-shank into proper position, and then the hook *c*, on being forced into place, is firmly confined therein by moving the link into its normal position, as shown in Fig. 1. In some cases I provide notches or depressions in the top surface of the shank and in the underside 15 of the brace portion above the hook *c*, for occupation by the link, and firmly securing it in its normal position.

Instead of a link composed of wire, I sometimes use a seamless sheet-metal link, *d*, Fig. 2c, this being a short length of a thin drawn metal tube, flattened, passed over the hook *b*, and then crimped, as shown, into close contact with the two portions of the wire.

While it will be necessary, for the purpose 25 of avoiding the liability of defacing a surface on which the hook is to be mounted, to have the link movable, as described, it is to be un-

derstood that said link may be permanently fixed in position without departure from one feature of my invention.

Having thus described my invention, I claim as new and desire to secure by Letters Patent—

1. A hat or coat hook composed of a single length of wire and having a screw-threaded shank, an upper hook, an underlying hook 35 composed of one terminal of the wire, and a coupling-link which is applied to and embraces a part of the wire in the shank, and also the underlying portion of the wire above the lower hook, substantially as described. 40

2. A hat or coat hook composed of a single length of wire having a screw-threaded shank, an upper hook, an underlying hook composed of one terminal of the wire, and a coupling-link which is applied to and embraces a part 45 of the wire in the shank, and also the underlying portion of the wire above the lower hook, and is movable to and fro on the shank, substantially as described, and for the purposes specified.

PURCHASES MILES.
